(57) CLAIM

The ornamental design for a ring with three rotating annular, as shown and described.

DESCRIPTION

FIG. 1 is a perspective view of the ring, the three annular being in a first angular position.

FIG. 2 is a perspective view of the ring, the three annular being in a second angular position.

FIG. 3 is a bottom view of the ring, the three annular being in said first position.

FIG. 4 is a top view of the ring, the three annular being in said first position.

FIG. 5 is a left side view of the ring, the three annular being in said first position.

FIG. 6 is a right side view of the ring, the three annular being in said first position.

FIG. 7 is a view of the top of FIG. 3; and,

FIG. 8 is a view from the bottom of FIG. 3.
